[57] CLAIM

The ornamental design for a commando armored transporter, as shown and described.

DESCRIPTION

FIG. 1 is a side elevational view of a commando armored transporter showing my new design, the opposite side being substantially a mirror image thereof;

FIG. 2 is a rear elevational view thereof;

FIG. 3 is a top plan view thereof; and

FIG. 4 is a front elevational view thereof.

FIG. 1

FIG. 2

FIG. 4
